RATCHET WRENCH

Theodore O. Rueb, Chicago, Ill., assignor to The Sherman-Klove Co., Chicago, Ill., a corporation of Delaware

Application May 28, 1938, Serial No. 210,599

2 Claims. (Cl. 192—43.1)

This invention relates to ratchet wrenches or ratchet devices and is particularly directed to a reversible type in which the adjustable pawls are mounted in the driving member and coat with a toothed portion of the driven member.

The principal object of the invention is to provide a ratchet wrench having enclosed adjustable pawls or driving dogs with simple and efficient means adapted to be actuated exteriorly of the wrench head for reversing the pawls.

Other objects are to provide a novel mounting for driving pawls or ratchet devices such as ratchet wrenches, and novel means for shifting the positions of the pawls into operative and inoperative positions and holding the same in such adjusted positions; to provide a ratchet wrench having a pair of driving pawls, manually operable means for swinging the pawls into and out of operating positions, a spring common to both of said pawls for holding the same in operating position, and means coacting with the manually operable means for holding the same in adjusted position; and to provide such other advantages and novel features in construction and operation as will appear more fully hereinafter.

In the accompanying drawing illustrating this invention,

Fig. 1 is a plan view;

Fig. 2 is a sectional plan view showing the pawls adjusted to one position;

Fig. 3 is a similar view showing the pawls adjusted for another position; and

Fig. 4 is a sectional view taken on the line 4—4 of Fig. 3.

In the particular form of the invention as shown in the drawing, 5 is a driving member comprising a head or body portion 6 and a handle 7 which may be formed integrally therewith as shown or it may be attached thereto in any well known manner. The head has an elongated and somewhat oval shaped opening 8 with an inwardly extending rib or flange 9 which provides shoulders on either side for receiving side plates 10 and 11, these plates being held in position by pins or rivets 12 and 13. The plates enclose and support a driven member 14 which comprises a work-engaging head or the like and which is shown with a projection 15 for receiving a wrench socket or other part or tool to be driven. The driven member has an enlarged circular central portion provided with teeth 16 and has trunnions or bearings 17 and 18 that engage with holes 19 and 20 in the plates 10 and 11 as clearly shown in Fig. 4.

The driving dogs or pawls 21 and 22 are mounted on the pins 12 and 13 and their ratchet-wheel engaging ends are preferably each provided with two teeth or engaging portions 23 which are adapted to engage with two of the teeth 16 for turning the driven member. The toothed ends of the pawls are urged toward the toothed wheel by means of a common spring 24 which is preferably U-shaped and has its ends bent to provide projections 25 and 26 which engage with holes in the outer faces of the pawls and tend to swing the free ends of the pawls toward each other or toward the driven member.

The pawls have rearwardly extending teeth or projections 27 and 28 which extend into a peripheral slot 29 in a reversing and holding plate or lever 30. The ends of the slot have substantially radial projections forming lugs or shoulders 31 and 32 for engagement with the projections 27 and 28 on the respective pawls. The plate 30 is carried on a pin or rivet 33 which has its bearing in a hole 34 in the top plate 10 and which is provided with a thumb-piece or lever 35 for rotating the same, this lever being located in a convenient position on the head so that it may be readily actuated by the thumb or finger of the user. When the lever 35 is moved to one extreme position as shown in Figure 2, one of the pawls, as for instance the pawl 22, is swung out of engagement with the ratchet wheel while the other pawl 21 remains in engagement for turning the wheel in the corresponding direction when the handle is actuated. When the thumb-piece 35 is moved to its opposite position the pawls will be reversed as shown in Figure 3 so that the pawl 22 will become the operating member. The plate or lever 30 and parts connected therewith are held in these adjusted positions by means of any suitable holding means, as for instance a ball or the like 36 which is mounted in a hole 37 in the flange 9 and which is pressed toward the plate by means of a spring 38, the opposite end of which engages with the plate 11. The plate 30 has two or more holes or recesses 39 and 40 which register with the ball 36 when the plate 30 is swung to its respective adjusting or reversing positions as described.

As the operation of the device is readily apparent from the above description, further explanation does not seem to be necessary but it will be noted that the parts may be changed or modified for different ratchet mechanisms or tools and therefore the invention should not be limited to the particular arrangement set forth

herein except as specified in the following claims, in which I claim:

- 5 1. In a ratchet mechanism, the combination of a driving member comprising a handle having a head at one end with an elongated opening therethrough, a peripheral projection extending inwardly around the opening, cover plates engaging with said projection with their outer surfaces substantially flush with the rim of the head, a driven member comprising a toothed ratchet wheel rotatably mounted in said plates and having a driving portion extending therefrom, pins through said plates adjacent to the ratchet wheel for holding the plates in position, 10 dogs mounted on said pins and adapted to engage with opposite portions of the ratchet wheel for turning the same in opposite directions, rearwardly extending projections on said dogs, a U-shaped spring engaging with the dogs and tending to hold their operating ends in position to engage with the ratchet wheel, a pin through one of said plates, a lever secured to said pin and engaging with the projections on the dogs for adjusting the dogs, holes in one face of said lever, a spring-pressed detent engageable with said holes for holding said lever in adjusted position, and a thumb-piece on the outer end of the pin outside of the head for swinging the same to adjust the dogs for reversing the ratcheting movement, substantially as described.
- 15 2. A new article of manufacture comprising a ratchet mechanism having in combination a relatively flat elongated head, a handle secured to said head, plates closing the sides of the head, a driven member including a ratchet wheel posi-

tioned between the plates and having trunnions engaging with the plates and a portion extending beyond the trunnions for engagement with a part to be turned, rivets extending through the plates and serving to hold the same in position, 5 oppositely disposed pawls mounted on the rivets and engageable with the opposite sides of the ratchet wheel respectively, a U-shaped spring having inwardly extending projections at the ends thereof engaging with the outer faces of the pawls and tending to bias the pawls toward the ratchet wheel, said pawls having rearwardly extending projections, a pin rotatably mounted in one of said plates, a reversing plate secured to said pin and positioned within the head and having a slot which is engaged by the projections on the pawls, said slot being sufficiently wide to permit the ratcheting movement of the pawls when in adjusted positions, and the sides of the slot serving to swing the pawls out of operative positions, a thumb lever secured to the pin and positioned on the outside of one of the first-named plates, said reversing plate having two spaced-apart recesses on its inner surface, the head having a transverse hole adjacent to the reversing plate, a spring in said hole, a ball engaging with the spring and pressed thereby against the reversing plate, said spring being held in position by means of one of the first-named head plates and the ball being adapted to engage with the respective recesses in the reversing plate to hold the same in adjusted positions.

THEODORE O. RUEB. 35
